(57) **CLAIM**

The ornamental design of a chair, as shown and described.

DESCRIPTION

FIG. 1 is a right perspective view of the chair showing my new design; and,

FIG. 2 is a left perspective view of the design shown in FIG. 1.

The rear of the decorative open pattern portion of the backrest is identical to the front of that portion. Likewise, the bottom of the decorative pattern of the seat portion is identical to the top of that portion.

1 Claim, 2 Drawing Sheets
